(57) **CLAIM**

The ornamental design for a pet bowl, as shown and described.

DESCRIPTION

FIG. 1 is a front, right, and top perspective view of a pet bowl, showing my design.

FIG. 2 is a front elevation view thereof.

FIG. 3 is a rear elevation view thereof.

FIG. 4 is a left side elevation view thereof.

FIG. 5 is a right side elevation view thereof.

FIG. 6 is a top plan view thereof.

FIG. 7 is a bottom plan view thereof; and,

FIG. 8 is a cross-sectional front view taken along and in the direction of line 8-8 in FIG. 2.

The drawings show broken lines that illustrate portions of the pet bowl. FIG. 2 show broken lines that represent the indicator of the cross-sectional view. The broken lines form no part of the claimed design.
